UNITED STATES PATENT OFFICE

2,143,684

ELECTRORESPONSIVE CONTROL SYSTEM

Guglielmo Camilli, Pittsfield, Mass., assignor to
General Electric Company, a corporation of
New York

Application July 31, 1936, Serial No. 93,662

7 Claims. (Cl. 171—119)

My invention relates to electro-responsive control systems and more particularly to improvements in voltage-responsive control systems utilizing glow tubes.

5 Electro-responsive control systems are adapted for use in arrangements for indicating, controlling and regulating various operating conditions such as current, voltage, pressure, temperature and numerous other similar conditions. While my 10 invention is capable of quite general application and it is not intended that it be limited to any particular application, it is particularly suitable as a main voltage responsive control means for an automatic voltage regulating system. The 15 most common type of voltage sensitive main control means for an automatic voltage regulating system is an electro-magnetic relay or contact making voltmeter which has a coil connected to respond to the voltage to be regulated and this 20 coil acts on an armature or solenoid core which actuates a contact making member. Two of the most important disadvantages of such an arrangement are that no positive contacts are made, especially when the voltage is slightly different from the normal value and the apparatus 25 is as delicate as an ordinary measuring instrument and requires the same careful handling and maintenance.

In the circuit of my invention these disadvantages have been eliminated, the circuit being relatively rugged and making and breaking contacts positively in response to very slight changes in voltage. The main voltage-sensitive element of 30 my circuit is a glow tube. Such a tube consists 35 of an envelope containing two electrodes and a suitable gas, such as neon, the pressure of which is reduced to the point of minimum impedance. It is well known that the voltage at which such a tube breaks down and passes current is remarkably constant and is largely independent of frequency and temperature.

An object of my invention is to provide a new and improved electro-responsive control system.

Another object of my invention is to provide a rugged and positively actuated voltage-sensitive control system.

A further object of my invention is to provide a novel voltage-sensitive circuit controlled by a glow tube.

50 My invention will be better understood from the following description taken in connection with the accompanying drawing and its scope will be pointed out in the appended claims.

55 Referring now to the single figure of the accompanying drawing, I have shown therein dia-

grammatically, by way of example, an embodiment of my invention for controlling an automatic voltage regulating system for a main electric circuit 1. My voltage-sensitive control system comprises a pair of control relays 2 and 3, the contacts of which, together with the contacts of a differential relay 4, complete control circuits which determine the direction of operation of a motor 5 for operating a regulator 6 for the voltage of circuit 1. Regulator 6 may be of any suitable 10 and well known type and is shown by way of example as an induction voltage regulator. The proper energization of the control relays 2 and 3 and the differential relay 4 in response to changes in voltage of circuit 1 is controlled by a sensitive 15 relay 7 under the control of a glow tube 8. Relays 2 and 3 are normally open relays in the sense that their contacts are open when they are deenergized. Relay 7, which is the only relay which needs to have a sensitive setting or adjustment, 20 is a normally closed relay. Differential relay 4 has a pair of opposed windings which are so arranged that when they are both energized the contacts of the relay are open and when either one is energized alone the contacts of the relay 25 are closed. Relay 2, which is arranged to be closed when the voltage of circuit 1 is low and which consequently may be referred to as the "raise" relay because it controls the operation of the regulator to raise the voltage, has its operating winding connected across the circuit 1 in series with one of the windings of the differential relay 4 and the contacts of the sensitive relay 7. Relay 3, which is arranged to be energized when the voltage of the circuit 1 is high and which 30 consequently may be referred to as the "lower" relay because it controls the operation of the regulator to lower the voltage, has its operating winding connected across the circuit 1 in series with the glow tube 8, the remaining winding of 35 the differential relay 4 and the operating winding of the sensitive relay 7.

The operation of the illustrated embodiment of my invention is as follows: Let it be assumed that it is desired to maintain the voltage of circuit 1 between 110 and 110½ volts. For such regulation a glow tube 8 is selected which breaks down when the voltage of circuit 1 is 110 volts and the relay 7 is so adjusted that it does not open its contacts until the voltage of circuit 1 50 is 110½ volts. Assume now that the voltage across circuit 1 is only 108 volts. Under these conditions current flows through the "raise" relay 2, through one of the windings of the differential relay 4 and through the normally closed contacts 55

of the relay 1. This causes "raise" relay 2 and differential relay 4 to close their contacts, which are in series in a circuit including the motor 5 and a suitable source of operating current for the motor such as a control battery 9. This causes the motor 5 to operate in such direction as to cause the regulator 6 to raise the voltage of circuit 1. When the voltage becomes 110 volts 5 the glow tube 8 breaks down causing current to flow through the operating winding of "lower" relay 3, the remaining winding of the differential relay 4 and the operating winding of the sensitive relay 1. This causes "lower" relay 3 to close its contacts and causes differential relay 4 to open its contacts because both of its windings are now operatively energized. Consequently, although both the "raise" relay 2 and the "lower" relay 3 are now closed the opening of the contacts of the differential relay 4 prevents the completion of either of the control circuits for the motor 5 and therefore the motor comes to rest and the regulator ceases to change the voltage of circuit 1. If now the voltage of circuit 1 should increase, 10 from any cause such as a reduction in load thereon or an increase in the voltage of the source of supply for this circuit, and this increase should exceed 110½ volts the sensitive relay 7 would open its contacts. This would cause deenergization of the "lower" relay 2 and of the uppermost one of the two windings of the differential relay 4. Consequently, relays 3 and 4 would now be closed 15 and as their contacts are in series in a circuit, with the motor 5 and the source 9, for causing reverse operation of the motor 5 the regulator will act to lower the voltage of circuit 1.

It will thus be seen that my system automatically responds to changes of voltage in circuit 1 in such a manner that below a certain voltage value one control circuit is controlled, above another voltage value the other control circuit is controlled and between both voltage values both control circuits are unchanged. By the term controlled I mean to include both the ordinary circuit opening or circuit closing type of control as well as the well known variable effective impedance type of control. The two voltage values may also be considered as defining a range or zone of voltage insensitivity above or below which the control circuits are selectively controlled. Furthermore, from another point of view, it will be seen that the two control circuits are selectively controlled when the voltage is above or below a predetermined value, corresponding to half way between the two above-mentioned voltage values, 20 by a predetermined amount, corresponding to half the difference between said voltage values, in either direction, respectively. The predetermined voltage value may be considered as the normal voltage value for the main regulated circuit.

While I have shown and described a particular embodiment of my invention, it will be obvious to those skilled in the art that changes and modifications can be made therein and I, therefore, aim in the appended claims to cover all such changes and modifications as fall within the true spirit and scope of my invention.

What I claim as new and desire to secure by Letters Patent of the United States is:

70 1. In a voltage-sensitive control system, in combination, an electric circuit, a differential relay provided with opposed actuating elements and having an actuated and a de-actuated condition, and means including a glow tube and a voltage sensitive relay for actuating said serially con-

nected differential relay when the voltage of said circuit is a predetermined amount above a normal value and for de-actuating said differential relay when said voltage is a predetermined amount below said normal value.

5 2. In combination, an electric circuit, a relatively sensitive relay having an operating winding and a set of contacts, a differential relay having two windings, and a glow tube connected across said circuit in series with the winding of said sensitive relay and one of the windings of said differential relay, the other winding of said differential relay being connected across said circuit in series with the contacts of said sensitive relay.

3. In combination, an electric circuit, a normally closed relatively sensitive relay having an operating winding and a set of contacts, a differential relay having two windings, and a glow tube connected across said circuit in series with the winding of said sensitive relay and one of the windings of said differential relay, the other winding of said differential relay being connected across said circuit in series with the contacts of said sensitive relay, said sensitive relay being set to open its contacts at a current appreciably 15 higher than the current corresponding to the minimum voltage required to break down said glow tube whereby at low and high values of voltage of said circuit the differential relay is actuated and at intermediate values of voltage 20 of said circuit said differential relay is de-actuated.

4. In combination, an electric circuit, a relatively sensitive relay having an operating winding and a set of contacts, a differential relay having 35 two windings, a glow tube connected across said circuit in series with the winding of said sensitive relay and one of the windings of said differential relay, the other winding of said differential relay being connected across said circuit in series with the contacts of said sensitive relay, said sensitive relay being set to open its contacts at a current appreciably higher than the current corresponding to the minimum voltage required to break down said glow tube whereby at low and high 45 voltages of said electric circuit the differential relay is actuated and at intermediate values of voltage of said electric circuit said differential relay is de-actuated, and control circuits controlled by said differential relay.

50 5. A voltage-sensitive control system comprising, in combination, an electric circuit, two normally open control relays, a differential relay having two windings, a normally closed sensitive relay, a glow tube, a connection across said circuit including the operating winding of one of said control relays, one of the windings of said differential relay and the contacts of said sensitive relay in series, another connection across said circuit including said glow tube, the winding of 55 the other control relay, the remaining winding of said differential relay and the winding of said sensitive relay in series, said sensitive relay being set to open its contacts at a current appreciably higher than the current corresponding to a value 60 of voltage of said circuit which is just sufficient to break down said glow tube whereby when the voltage of said circuit is above the break-down value of said glow tube but below the value at which said sensitive relay opens its contacts said differential relay will have both of its windings 65 energized and its contacts open, and separate control circuits each including the contacts of one of said control relays and both including the contacts of said differential relay.

6. A voltage-sensitive system comprising, in combination, a main circuit, a pair of normally open secondary circuits adapted respectively to be closed when the voltage of said main circuit has different predetermined values, a glow tube connected to be responsive to the voltage of said main circuit and having the characteristic of breaking down from a non-conducting to a conducting state at a fixed voltage which is between 5 said values, means responsive to the absence of current in said glow tube for closing one of said secondary circuits, means responsive to the breakdown of said glow tube for opening said closed secondary circuit, and means responsive to a 10 predetermined increase in current through said glow tube for closing the other of said secondary circuits.

7. An automatic voltage regulator system comprising, in combination, a main circuit whose

voltage is to be regulated, a pair of normally open voltage raise and lower circuits adapted respectively to be closed when the voltage of said main circuit has predetermined low and high values, a glow tube connected to be responsive to the voltage of said main circuit and having the characteristic of breaking down from a non-conducting to a conducting current at a fixed voltage which is between said values, means responsive to the absence of current in said glow tube for closing said raise circuit, means responsive to the breakdown of said glow tube for opening said raise circuit, means responsive to a predetermined increase in current through said glow tube for closing said lower circuit, and reversible voltage regulating means in said main circuit whose direction of operation is controlled respectively by the closure of said raise and lower circuits. 15

GUGLIELMO CAMILLI.

CERTIFICATE OF CORRECTION.

Patent No. 2,143,684.

January 10, 1939.

GUGLIELMO CAMILLI.

It is hereby certified that error appears in the printed specification of the above numbered patent requiring correction as follows: Page 1, second column, line 46, after the numeral "110" insert the word volts; page 2, first column, line 75, claim 1, strike out the words "for actuating said" and insert the same before "differential", second column, line 1, same claim; and that the said Letters Patent should be read with this correction therein that the same may conform to the record of the case in the Patent Office.

Signed and sealed this 28th day of February, A.D. 1939.

Henry Van Arsdale.

(Seal)

Acting Commissioner of Patents.
